UNITED STATES PATENT OFFICE.

ALFRED L. DRUCKEMILLER, OF GREAT FALLS, MONTANA.

FRAMING-SQUARE.

1,240,035.

Specification of Letters Patent. Patented Sept. 11, 1917.

Application filed October 7, 1916. Serial No. 124,343.

To all whom it may concern:

Be it known that I, ALFRED L. DRUCKEMILLER, a citizen of the United States, and a resident of Great Falls, in the county of 5 Cascade and State of Montana, have invented a certain new and useful Improvement in Framing-Squares, of which the following is a specification.

My invention is an improvement in framing squares, and has for its object to provide a square of the character specified which may be used as a bevel, miter, or tri-square, and by means of which common 10 rafters, jack rafter, and hip and valley 15 rafters may be laid off correctly merely by varying the position of the parts, and wherein other mechanism is provided for laying off mitered cuts for polygons.

In the drawings:

20 Figure 1 is a side view of the improved square with parts in section;

Fig. 2 is a similar view from the opposite side;

25 Fig. 3 is a side view with parts in different positions;

Figs. 4 and 6 are sections on the lines 4—4 and 6—6 respectively of Fig. 1, each view looking in the direction of the arrows adjacent to the lines;

30 Fig. 5 is a section on the line 5—5 of Fig. 2, looking in the direction of the arrow adjacent to the line.

The present embodiment of the invention 35 comprises a handle portion 1 of wood or the like, having in one side edge a longitudinally extending groove or recess 2, which is adapted to receive a straight blade 3 of metal or the like, the said straight blade 3 being pivoted to the end of the handle by 40 means of a screw bolt 4 which is provided with a wing nut 5 for tightening the blade with respect to the handle.

It will be understood that the handle is 45 cut away at the opposite side from the passage at the end adjacent to the pivotal connection as indicated at 1^a in order that the side walls of the passage may be tightened on the blade.

At about the center of the straight blade 50 3 a curved blade or protractor 6 is connected, the said curved blade or protractor having a dove-tail lug 7 at the connected end which is received in a similarly shaped opening in the blade 3, and a screw 8 is passed 55 through the lug and the blade 3 to hold the parts together. The bottom of the groove

or passage 2 is cut away as indicated at 9 at the plate 6 in order that the said blade may pass through the handle portion, as shown in Figs. 1, 2, and 3, when the blade 60 3 is swung with respect to the handle portion 1. The blade 3 is provided with a scale 10 laid off in inches and fractions thereof, and the protractor blade 6 has a number of scales. On one face and at the center is arranged a scale 11, the graduations of the scale being designated by the numerals 3 to 12 inclusive, and this scale is adapted to give the plumb cut on common rafters. The numerals 3 to 12 refer to the rise of the roof 70 to the foot runs of rafters. A three inch rise to the foot represents one-eighth pitch, a five inch rise five-twenty-fourths pitch, while a twelve inch rise represents one-half pitch.

75 The face of the blade is divided into three spaces by longitudinally extending curved lines, and the scale 11 is at the center of the blade. At the convex edge a scale 12 is provided for laying off the base cut of common rafters, and on the concave edge a scale 13 is provided for laying off the bevel cut on jack rafters. Each of these scales has its graduations designated by the numerals 3 to 12 inclusive, and each space bears a 80 legend indicating the purpose of the scale; as for instance, the central scale has a legend "Plumb cut on common rafters," while the scales 12 and 13 have legends: "Base cut on common rafters" and "Bevel 85 cut on jack rafters," respectively.

On the opposite face the blade is also divided by curved lines into three spaces, and each space bears a scale. The central scale 14 is for laying off plumb cuts of valley 90 and hip rafters. The scale 15 at the concave edge is for laying off the bevel cut on valley and hip rafters, while the scale 16 on the concave edge is for laying off the base cut of such rafters. The graduations of each 100 scale are designated by the numerals 3 to 12 inclusive, and adjacent to each scale is a legend denoting the purpose of the scale.

On the concave edge of the blade there is a scale indicated at 17 for indicating degree cuts or graduations to be spaced to provide two and one-half degree cuts. The convex edge has a scale indicated at 18 in Fig. 5 for laying off the mitered cuts for polygons having from six to twelve sides.

105 110 The scales 11, 12, 13, 14, 15, 16, 17, and 18 are so spaced as to give the desired cut

when the graduations on the protractor blade are brought into register with the side edge of the handle portion, that is, with the edge adjacent to the blade 3.

- 5 The improved square is intended to be used with the ordinary rafter chart, and in order to obtain the plumb base cut of common rafters with the instrument, the blade 3 is moved until the numeral 8 on the line 10 plumb cut on common rafters registers with the right side of the handle in Fig. 1. The length of the rafter is determined by referring to the rafter chart for common rafters. For instance, in a building sixteen 15 feet wide, under the numeral 16 of the chart and in line with the numeral 8 will be found on the chart the length of rafter for sixteen feet, namely, nine feet, seven and a half inches. One end of the rafter is marked 20 with a square line on top and with the pivotal connection 4 toward the end of the rafter, the line being marked along the straight blade. The length of the rafter is then laid off, which may be done by the 25 blade 10, the said blade being graduated in inches. The square is now reset to the numeral 8 on the line indicating base cut for common rafters and the bevel is laid off at the other end. The scale 18 is a scale for 30 laying off polygons of from six to twelve sides. For seven sides the register is set on the graduation marked 7 and the ends of the studding to be cut are laid off along the edge of the blade 3. The ends of the pieces 35 of studding are laid off in the same manner,

and when they are assembled there will be a perfect heptagon. The blade 6 is merely an indicating blade, and the marking lines are drawn along the edge of the blade 3. The graduations on the blade 6 are merely to indicate the position of the blade 3 with respect to the handle. In laying off, the handle is laid alongside one edge of the piece to be cut, with the blade 3 extending across the piece. 40 45

I claim:

A framing square comprising a handle portion having in one edge thereof a longitudinally extending groove or recess, the bottom of the groove being cut away at one end, a straight blade pivoted at the said end and adapted to fit within the groove or passage, means for clamping the side walls of the groove or passage on the blade at the said end to fix the same with respect to the handle, a curved or protractor blade connected with the straight blade at approximately the center thereof and extending through the bottom wall, said bottom wall being cut away to permit the passage of the protractor blade, said protractor blade being provided on its opposite face with scales designating the plumb, bevel, and base cuts of valley and hip rafters, the plumb and base cuts of common rafters, and the bevel 35 cut of jack rafters, and on its edges with degree scales and scales for bevel cuts for polygons.

ALFRED L. DRUCKEMILLER.
